CLAIM

The ornamental design for a training device, as shown and described.

DESCRIPTION

The entire disclosure of U.S. patent application Ser. No. 09/034,524, which is now U.S. Pat. No. 5,964,683, is incorporated herein by reference.

FIG. 1 is a perspective view showing the back, bottom and left side views of the training device according to the invention;

FIG. 2 is a view of the left side of the training device; FIG. 3 is a view of the back side of the training device; FIG. 4 is a view of the front side of the training device; FIG. 5 is a view of the bottom of the training device; and, FIG. 6 is a view of the top of the training device.

The right side view of the training device is a mirror image of the view shown in FIG. 2.
